FOREIGN PATENT DOCUMENTS

DE 3632537 4/1988

Primary Examiner—Elizabeth A Albert
Assistant Examiner—Kelley A Donnelly(74) *Attorney, Agent, or Firm*—Seyed Kaveh E. Rashidi-Yazd, Esq.; Ryan A. Schneider, Esq.; Troutman Sanders LLP(57) **CLAIM**

The ornamental design for an engaging bracket, as shown and described.

DESCRIPTION

FIG. 1 is a perspective, side view of an engaging bracket;

FIG. 2 is a top view thereof;

FIG. 3 is a bottom view thereof;

FIG. 4 is a side view thereof;

FIG. 5 is another side view thereof;

FIG. 6 is a front view thereof; and,

FIG. 7 is a rear view thereof.

The broken, dashed lines shown in the various figures depicting embodiments of the invention are included for the purpose of illustrating environment and do not form any part of the claimed design.
